UNITED STATES PATENT OFFICE.

FREDERICK B. VOEGELI, OF EASTON, PENNSYLVANIA.

LENGTH RECORD AND AUTOMATIC MACHINE FOR MAKING SAME.

Application filed August 31, 1921. Serial No. 497,310.

The invention relates broadly to mechanism primarily intended for use by cloth-finshers, for producing automatically a permanent and readily-legible record showing not only the total length of a plurality of pieces of cloth stitched together to be subjected to converting (as in bleaching, dyeing, etc.) but also the respective lengths of the individual pieces. The invention may likewise be employed in the measurement of other articles such as lengths of rope, cable, etc.

The invention consists broadly of such permanent record and of the co-acting mechanisms for producing it automatically. More particularly, one feature of the invention consists of suitable mechanism whereby the passage of successive transverse seams (each produced by stitching together the adjacent ends of two pieces) will actuate a marker to produce a record indicating the distances between the successive seams,—thus affording a permanent record of the individual lengths of the successive pieces, and of the total aggregate length also. The invention comprises further the various features of construction and arrangement hereinafter set forth and claimed.

The invention is not limited to such use by cloth-finshers specifically in converting, but is susceptible of employment in other services; yet the invention will be best understood by describing one embodiment thereof as employed in that particular service. The finisher receives the product of the mill in pieces of different lengths, for converting (which term comprises bleaching, dyeing, finishing or the like), resulting sometimes in shrinking and sometimes in stretching the cloth. The mill or other customer is supposed to have measured the lengths of the pieces delivered by him, and the finisher is supposed to make measurements of his own. But heretofore the second measurement has required of the finisher time and labor, which it is one of the objects of the present invention to eliminate. Moreover, the measurements by the finisher may not tally with the previous measurements by his customer; and this leads to disputes, which it is another object of the present invention to prevent.

It is more economical to do the converting by continuous operation. For this purpose, in carrying on their operations, it is the practice of finishers to assign a particular number or other symbol to designate the

product of each customer, and to mark this number indelibly (as upon the margin) upon every piece of cloth received from that particular customer; moreover, each piece of cloth received from any customer is additionally marked with its own serial number. A plurality of pieces from one customer will then be stitched together, end to end, and run successively through the desired converting-treatment.

According to this present invention, suitable mechanism is provided whereby the total length (in yards or other units) of the combined pieces is automatically recorded permanently upon a suitable tape by uniformly-spaced punctures or other markings, corresponding to units of length; and, preferably, by an additional series of uniformly-spaced markings corresponding to some suitable multiple of said unit, as every tenth yard; and, finally, the passing of every seam (uniting two pieces) is similarly recorded automatically on the same tape by markings whose spacings correspond to the respective length of the pieces.

The invention will be best understood by reference to the annexed drawings, which set forth a preferred embodiment thereof, and in which:

Fig. 1 is a vertical section on the line 1—1 of Fig. 2 presenting the cloth-measuring rolls in end elevation;

Fig. 2 is an elevation, viewed from the left of Fig. 1, and showing partly in section the tape-puncturing mechanism, and the main tape-carrying wheel;

Fig. 3 is a side elevation, viewed from the right of Fig. 2, of the tape-carrying mechanism;

Figs. 4 and 5 are details, showing a face-view and edge-view respectively, of gearing for actuating the recording-instrumentalities; and

Fig. 6 represents a portion of the tape, presenting the permanent record, the size of the punctures being greatly exaggerated.

Referring first to Fig. 1: In fixed bearings, preferably ball-bearings, on upright standards 1 is journalled the shaft 2 of the main or cloth-measuring roll 3, one end of said shaft projecting beyond the standard (for actuating the recording-instrumentalities). Normally resting upon the top of said main roll is the upper cloth-roll 4, having a floating-shaft 5 whose ends are confined in vertical guideways so as to permit slight up and

down movements of said roll 4. As below set forth, the passage between said rolls of a seam (uniting the adjacent ends of two successive pieces of cloth) raises the upper 5 roll slightly and then allows it to drop back; and such vertical movement of roll 4 operates to produce a permanent record of the seam. Tension-bars 6—7—8 extend transversely between the standards 1. At 9—9 etc. is the 10 edge or section of the cloth being treated, its thickness being greatly exaggerated. It has been first passed over the first tension-bar 6 and under the second bar 7 and over the third bar 8, thence under and partly around 15 the periphery of the main measuring-roll 3 and between the rolls, and thence in opposite direction partly around the upper roll 4,—thereafter to be drawn along (by mechanism not shown) in the direction indicated by the arrow, for the bleaching, dyeing, or other desired treatment. The periphery of said main or cloth-measuring-roll 3 is preferably roughened, as by a surfacing of carborundum or sandpaper, to ensure that 20 25 the cloth will rotate the measuring-roll (without slipping along its periphery).

This rotation imparted to said roll 3 by the cloth propels a tape at correlated speed. The circumferential dimension of said 30 measuring-roll 3 is predetermined, say exactly thirty-six inches; and suitable mechanisms (to be described) produce on said tape a permanent record for each complete revolution and for each ten revolutions of said 35 roll 3, thereby indicating each complete yard and each complete ten yards of cloth that passes said roll. At 10 is indicated a seam (joining two successive pieces of cloth) which has just passed between the two rolls. 40 The passage of said seam has slightly lifted the upper roll (to an extent corresponding to the additional thickness of said seam) and said upper roll has dropped back to its normal position. As 45 below described, said upward movement has caused a suitable marker to make a permanent mark on said tape; so that the distance between two such marks correspond to the length of the piece, from one seam to the next.

50 Referring next to Figs. 2 and 3, 11 represents a suitably-supported table, located near one of said standards 1, at a level a little above that of said shaft 2, for supporting the recording-instrumentalities, which latter 55 comprise the above-mentioned tape, three markers here shown as puncturing-needles, and means for actuating said tape and needles. The actuation is effected by an actuating-shaft 12, which is either the afore- 60 said extension of shaft 2 or a shaft connected thereto and revolving therewith at the same rate. This shaft 12 is suspended from said table 11, as by suitable bearings 13. Said table is slotted at 14, to receive the periphery 65 of the tape-carrying wheel suitably jour-

nalled beneath the table so that the top of its periphery extends into said slot to about the level of the upper surface of said table; while directly above said slot is secured the frame for the needle-carrying bars. For supporting said tape-carrying wheel two brackets or castings of substantially the construction shown in Fig. 3 are secured to the under surface of said table, each consisting of the two downwardly-inclined suspension-members 70 75 15—15 whose lower ends are connected by the hub 16 to carry the horizontal members 17—17. The tape-carrying wheel 18 has its shaft journaled in said hubs 16, preferably on ball-bearings. The outer ends of said 80 horizontal members 17—17 are slotted to receive the shafts of the tape-spools 19 and 20, one (as 19) a magazine-spool provided with a length of tape 21 wound up thereon, and the other (as 20) a take-up spool. 85

From the under side of said magazine-spool 19, the tape has first been drawn over the upper half of the periphery of said main wheel 18, to be passed down and around the take-up spool 20. The shaft of said spools are drawn towards said main wheel 18, and towards each other (in said slotted ends), by the spring or springs 22, whereby the tape is clamped upon said wheel 18, and whereby 90 rotation imparted to said wheel (as below 95 described) will frictionally rotate the two spools, drawing the tape off from the magazine 19, over said main wheel 18, and winding it upon the take-up 20, the tape thus passing along within said slot 14, to be acted 100 upon by the recording-needles (as below described). If desired, on each of the bracket-members 15 may be a sleeve 23, having pivoted on its offset outer end a roller 24 riding on the periphery of wheel 18 and 105 forced inward by a spring 25 that bears against suitable collars on said sleeve and member respectively. These rollers assist in maintaining the tape firmly and flatly 110 against the periphery of said wheel 18. 115 Preferably, also, the periphery of said tape-propelling wheel 18 is provided with two marginal flanges, producing a circumferential trough, into which the two rollers and the two spools with their convolutions of 120 tape are forced by their respective springs; and the floor of said trough is provided with three parallel circumferential grooves, one for each of the recording-needles, each 125 groove affording clearance for its appropriate needle-tip on penetrating the tape.

To said actuating-shaft 12, near its end and adjacent said tape-propeller 18, is secured the finger 26 (see Figs. 1 and 4). Opposite said finger a counter-shaft 27 (see 125 also Fig. 5) is journaled in suitable bearings 28—28' beneath said table 11. On one end of said counter-shaft, within the orbit of said finger, is the star-wheel 29, here shown as having twenty teeth; while on the other 130

end of said shaft is the pinion 30, in mesh with internal-gear 31 carried by said tape-carrying wheel 18. Each complete revolution of said cloth-measuring roll 3, and of 5 said shaft 12, advances said star-wheel and tape-carrier one tooth or step only, the actual length of each step depending upon the number and dimensions of the teeth of the gearings; and a coil-spring 32 (bearing against 10 said star-wheel and bearing 28 respectively) maintains said star-wheel and pinion in each position. For each complete revolution of the cloth-measuring wheel 3, therefore, the tape is advanced a uniform distance, and 15 held there by spring 32; and a puncture is to be produced in the tape (as below set forth) to represent one yard of cloth.

Directly above said slot 14 and the tape-carrier 18, is secured the frame 33, a casting, 20 to support the vertically-reciprocable bars that carry the needles for puncturing the tape. One of these bars, as 34, preferably the central one, carries at its lower end a needle for puncturing the tape to indicate 25 units of length, as yards. This bar 34 is actuated by a lever 35, fulcrumed on said frame 33 and at one end pivoted to said bar 34, while its other end is pivotally connected to a cam-strap 36 which surrounds an eccentric cam 37 fast on said actuating-shaft 12. Suitable lost-motion is provided at said pivots, as by slightly slotting, to permit free movement of the parts. Said cam is so adjusted on said shaft that it does not attain its 30 upper position (whereby the needle is forced into the tape) until after the tape has come to rest after being advanced one step. By means of this needle-actuating structure and the tape-feed previously described, each 35 complete revolution of the main cloth-measuring wheel causes one complete revolution of said actuating shaft 12, and thereby causes said finger 26 and cam 37 to advance the tape one step and thereafter cause the 40 unit-needle to produce one puncture in the tape; so that there is thus made a permanent record of the yardage, as indicated in Fig. 6 by the central row 38 of equidistant punctures corresponding to the number of 45 yards (or other units) of cloth that have passed over the measuring-roll.

Still referring to Figs. 4 and 5, in connection with Fig. 2, on one face of said star-wheel 29 (on countershaft 27) are two 50 diametrically-opposite lugs or detents 39-39, into whose orbit extends the offset lower end of an arm 40 whose upper end is connected to a second needle-bar 41, which is mounted in frame 33 for vertical reciprocation. Said bar 41 is normally maintained in its upper position by a spring 42, bearing against suitable collars on said frame and bar respectively; while the lower end of said bar 41 carries a needle adapted 55 to puncture the tape at the predetermined

(ten-yard) intervals, producing the row 43 of equidistant (ten-yard) punctures, as seen in Fig. 6, parallel with row 38 of unit-length punctures. In the present instance, inasmuch as there are twenty teeth on the 70 star-wheel and two detents, the arm 40 and the needle-bar 41 will be drawn down once for every ten revolutions of cloth-roll 3 and actuating shaft 12, and each puncture of 75 said row 43 will thus represent ten yards of cloth. Preferably the aforesaid finger 26 is so adjusted on said actuating-shaft that it will function to engage the star-wheel 29 and advance it to puncture a ten-yard hole simultaneously with the functioning of the 80 first-named needle in producing one of its punctures; each ten-yard hole will thus be located by the side of every tenth one-yard hole.

On suitable supports, such as the upper portion of standard 1, are two pivots 44-44 (Figs. 1 and 2) on which are fulcrumed respectively the members of a pair of diagonal levers 45-45, whose overlapped 85 shorter inner ends are slotted and receive 90 the end of the above-named floating-shaft 5 (of the upper cloth-wheel 4); while to the longer outer ends of these levers are pivoted respectively the links 46-46, whose overlapped inner ends are pivotally connected 95 to the upper end of a third needle-carrying bar 47, which is mounted to reciprocate vertically in said frame 33. Each time a seam in the length of cloth, as 10 in Fig. 1, passes under said roll 4, it lifts the roll 100 and its floating-shaft 5, and thereby lifts the short upper arms of the diagonal levers 45 (a distance corresponding to the extra thickness of said seam); this forces downward the longer outer ends of said levers, which in turn (through links 46) force 105 downward said needle-bar 47, thereby causing its needle to puncture the tape on wheel 18, thus making a permanent record of said seam. Suitable springs, including a spring 110 48, restore said levers and needle to their initial position as soon as the seam 10 has passed on. As indicated in Fig. 1, the outer or lower arms of the levers 45 are preferably longer than their inner arms, thus increasing the length of stroke of the needle-bar 115 47 with its needle. Each time a seam thus passes between the cloth-rolls, the tape receives a puncture, as at 49 in Fig. 6.

The new permanent record thus automatically produced, as indicated in Fig. 6, consists of a tape presenting three parallel rows of markings, such as punctures; whereof one (the central row, 38) consists of a succession or series of uniformly-spaced markings; the second consists likewise of a series of markings (43) but spaced at a multiple distance, say ten times that of the first row; while the third consists of markings (such as 49) whose spacings vary in accordance 120 125 130 135 140

with the lengths of the respective pieces of cloth. The total length of the cloth which has passed through the rolls can be ascertained at any time by referring to the tape and counting the number of punctures in the unit-row 38, which will be simplified by counting the ten-yard punctures in the second row 43. If desired, while each piece is still passing through rolls 3 and 4, the individual serial number of that particular piece can be marked upon the tape. By ascertaining the number of yards between any two punctures of the third row (as 49, etc.) the length of the corresponding piece of cloth can be ascertained.

Any suitable or desirable revolution-counter may be applied to the main mechanism at any suitable or desirable point. Such a revolution-counter 50 is conventionally represented, in Fig. 2, as applied to the actuating-shaft 12. Such device will indicate the total length of the cloth, and the figure it gives will tally with the total length recorded at the same stage by the tape; but such counters do not produce a permanent record; and therefore are of no other value than to confirm, at the time, the correctness of the permanent record on the tape.

All the details of the invention have thus been set forth fully, but only for the sake of clearness, since the invention is not limited to the precise construction and arrangement herein set forth. For example, it will be understood that this recording-machine can either be built into the converting-mechanism or constructed as a separate mechanism susceptible of being operatively connected to the converting mechanism in any suitable or preferred manner, so long as the movement imparted to the tape and the actuation of the needles synchronize with the movement of the cloth. It will likewise be understood that instead of making the record by punching holes in a tape, it could be made by marking with ink or other suitable medium; that instead of recording every yard (thirty-six inches) and every ten yards, the recording might be in some other unit and of some other multiple than ten. Moreover, the needle for making a mark at each unit of length, together with its actuating mechanism, may be dispensed with, and a suitable scale previously provided on the tape as by printing may be used as a reference instead of the equidistant unitary punctures 38 heretofore described. Finally, parts of the invention can be used to the exclusion of other parts, parts can be transposed or inverted, and modifications of various features can be employed, without in any case departing from the spirit of the invention.

What I claim is:

1. As a new article of manufacture produced in the measurement of pieces of goods,

a length-record consisting of a suitable medium such as tape presenting three parallel rows of markings, the markings of one row being equidistant to constitute a scale whose successive uniform spacings are each of a length that bears a fixed ratio to a standard unit of length, the markings of the second row being separated by uniform spacings each of a length that corresponds at that same ratio to a fixed multiple of said standard unit, and the markings of the third row being separated by spacings whose successive lengths are respectively proportional at that same ratio to the successive lengths of the different pieces constituting the entire goods measured.

2. As a new article of manufacture produced in the measurement of pieces of goods, a length-record consisting of a suitable medium such as tape presenting at least two parallel rows of markings, the markings of one row being equidistant to constitute a scale whose successive uniform spacings are each of a length that bears a fixed ratio to a standard unit of length, and the markings of the other row being separated by spacings whose successive lengths are respectively proportional at that same ratio to the successive lengths of the different pieces constituting the entire goods measured.

3. As a new article of manufacture produced in the measurement of pieces of goods, a length-record consisting of a suitable medium such as tape presenting equidistant markings to constitute a scale whose successive uniform spacings are of a length that bears a fixed ratio to a standard unit of length, and a number of other markings separated by spacings whose successive lengths are respectively proportional at that same ratio to the successive lengths of the different pieces constituting the entire goods measured.

4. In a cloth-measuring machine, the combination of a measuring-roll rotated in accordance with the travel thereover of cloth to be measured, a record-medium such as tape intermittently propelled a uniform step by means operatively connected to said roll, said roll having means to cause said first-named means to operate at each complete revolution of said roll and then remain stationary during the rest of said revolution, means actuated by said roll to produce on said medium while at rest a marking such as a puncture to constitute a row of markings, additional means actuated by said roll once in each predetermined multiple of such complete revolution to produce on said medium a second row of markings, one marking for each multiple aforesaid, and still additional means actuated by the passing over said roll of each seam in the cloth for producing on said medium a third row of markings.

5. In a cloth-measuring machine, the com-

- bination of a measuring-roll rotated in accordance with the travel thereover of cloth to be measured, a record-medium such as tape propelled a uniform step at each complete revolution of said roll, a recording-device such as a puncturing-needle actuated at each one of said revolutions to produce as by a puncture on said medium its record of said complete revolution, a second recording-device actuated at each predetermined multiple of such revolution to produce on said medium its record of said multiple of revolutions, and a third recording-device actuated at the passing over said roll of each seam in the cloth to produce on said medium its own record of each seam. 65
- 5 6. In a cloth-measuring machine, the combination of a measuring-roll rotated in accordance with the travel thereover of cloth to be measured, a record-medium such as tape intermittently propelled in uniform steps by means operatively connected to said roll, said roll having means to cause said first-named means to operate at each complete revolution of said roll, a recording-device such as a puncturing-needle actuated at each of said revolutions to produce on said medium its record of such complete revolution, and a second recording-device actuated 70 at the passing over of such roll of each seam in the cloth to produce on said medium its own record of each seam. 80
- 20 7. In a cloth-measuring machine, the combination of a measuring-roll rotated in accordance with the travel thereover of cloth to be measured, a superposed cloth-roll for pressing against said measuring-roll the cloth passing between said rolls, a tape-carrying wheel for presenting a supply of tape, means actuated once by said measuring-roll each time it makes a complete revolution to advance said tape-wheel with its tape one uniform step and then let the same come to rest, a puncturing-needle actuated 85 by said measuring-roll to produce in said tape while at rest one puncture for each complete revolution, another puncturing-needle, and means actuated by the lifting of said floating-roll by the passing thereunder of each seam in said cloth to cause the last-named needle to puncture said tape once for each seam. 95
- 30 8. In a cloth-measuring machine, the combination of a measuring-roll rotated in accordance with the travel thereover of cloth to be measured, a superposed floating cloth-roll for pressing against said measuring-roll the cloth passing between said rolls, a tape-carrying wheel for presenting a supply of tape, means actuated by said measuring-roll to propel said tape-wheel with its tape, a puncturing-needle, and means actuated by said floating-roll as it is lifted by the passing thereunder of each seam in said cloth to cause said needle to puncture said tape once for each seam. 100
- 40 9. In a cloth-measuring machine, the combination of a measuring-roll rotated in accordance with the travel thereover of cloth to be measured, a finger and a cam rotated in accordance with the revolutions of said roll, a star-wheel engaged by each revolution of said finger for intermittent rotation, a tape propelled intermittently by the movements of said star-wheel, a reciprocatory needle actuated by each revolution of said cam to puncture said tape, successive actuations producing a row of equidistant punctures, a detent on said star-wheel, a second reciprocatory needle alongside the first and actuated by said detent to puncture said tape in a parallel row of equidistant but wider-spaced punctures, a third reciprocatory needle alongside the first two, and means actuated by the passing over said measuring-roll of a seam in the cloth for causing the third needle to mark said tape with one puncture for each seam. 105
- 50 10. In a cloth-measuring machine, the combination of a measuring-roll rotated in accordance with the travel thereover of cloth to be measured, a finger and a cam rotated by and in accordance with the revolutions of said roll, a star-wheel engaged by each revolution of said finger for intermittent rotation, a tape propelled intermittently by the movements of said star-wheel, a reciprocatory needle actuated by each revolution of said cam to puncture said tape, successive actuations producing a row of equidistant punctures, a detent on said star-wheel, and a second reciprocatory needle alongside the first and actuated by said detent to puncture said tape in a parallel row of equidistant but wider-spaced punctures. 110
- 60 11. In a cloth-measuring machine, the combination of a measuring-roll rotated in accordance with travel thereover of cloth to be measured, a finger and a cam rotated in accordance with the revolutions of said roll, a star-wheel rotated by said finger, a wheel presenting a supply of tape and propelled by said star-wheel, and a reciprocatory needle actuated by said cam to puncture said tape. 115
- 70 12. In a cloth-measuring machine, the combination of a measuring-roll rotated in accordance with travel thereover of cloth to be measured, a cam rotating in accordance with the revolutions of said roll, a wheel presenting a supply of tape, means actuated by said roll to advance said tape, and a reciprocatory needle actuated by said cam to puncture said tape. 120
- 80 13. In a cloth-measuring machine, the combination of a measuring-roll rotated in accordance with the travel thereover of cloth to be measured, a superposed floating cloth-roll for pressing against said measuring-roll

- the cloth passing between said rolls and susceptible of being lifted by each seam passing thereunder, levers actuated by each lift of said floating-roll, a record-medium such as 5 tape propelled in accordance with the revolutions of said measuring-roll, and means such as a reciprocatory needle actuated by said levers to impart to said tape a record such as a puncture for each seam.
- 10 14. In a cloth-measuring machine, the combination of a cloth-measuring roll rotated in accordance with the travel of cloth to be measured, a finger and a cam rotated in accordance with the revolutions of said 15 roll, a tape-carrier propelled by said finger, and a reciprocatory needle actuated by said cam and adapted to puncture the tape on said carrier.
- 15 14. In a cloth-measuring machine, the combination of a cloth measuring-roll rotated in accordance with the travel thereover of cloth to be measured, a finger rotated in accordance with the revolutions of said roll, a star-wheel rotated by the intermittent engagement of said finger, a pinion rotating with said star-wheel, tape-carrying mechanism propelled by said pinion, and two marking-devices such as reciprocatory needles which are severally actuated to mark on 20 the tape of said carrier by each complete revolution of said roll and of said star-wheel respectively.
16. In a cloth-measuring machine, the combination of a cloth-measuring roll rotated in accordance with the travel thereover of cloth to be measured, a record-medium such as 25 tape advanced one step forward by each revolution of said roll, a recording-device such as a reciprocatory needle actuated by 30 said roll to produce a marking on said medium, successive actuations producing a row of equidistant markings corresponding to the number of revolutions, and another recording-device actuated by said roll and by 35 the passing thereover of a seam in the cloth to produce on said medium one marking for each seam.
17. In a cloth-measuring machine, the combination of a cloth-measuring roll rotated in accordance with the travel thereover of cloth to be measured, a superposed floating roll for pressing against said measuring-roll the cloth passing between said rolls, tape-carrying mechanism propelled for and 40 by each revolution of said measuring-roll, a marking-device such as a reciprocatory needle for marking upon the tape presented by said mechanism, and means actuated by the lift imparted to said floating roll by the 45 passing thereunder of each cloth-seam for causing said marking-device to mark on said tape.
18. In a cloth-measuring machine, the combination of a cloth-measuring roll rotated in accordance with the travel thereover 50 of cloth to be measured, a superposed floating cloth-roll for pressing against said measuring-roll the cloth passing between said rolls, tape-carrying mechanism propelled by means operatively connected with said measuring-roll, said roll having means to cause said mechanism to be propelled a definite distance for each complete revolution of said measuring-roll, a marking-device such as a reciprocatory needle for marking upon the 55 tape presented by said mechanism, means actuated at each lift imparted to said floating roll by the passing thereunder of each cloth-seam for causing said marking device to mark on said tape, and an additional marking device actuated at each revolution of said measuring-roll to apply on said tape a row of equidistant markings.
19. In a cloth-measuring machine, the combination of a measuring-roll rotated in accordance with the travel thereover of cloth to be measured, suitable mechanism for presenting a supply of tape, suitable mechanism actuated once at each complete revolution of said measuring-roll to produce on 60 said tape equidistant markings, a floating cloth-roll superposed above said measuring-roll for pressing against it the cloth passing between said rolls and susceptible of being lifted by the passing thereunder of a seam in the cloth, a reciprocatory marking-device such as a needle positioned for marking upon said tape, a pair of levers having their overlapped inner ends slotted to receive the shaft of said floating-roll so as to be moved by said roll on being lifted, and links pivoted at their outer ends to the outer ends of said levers and having their inner ends connected to said marking-device, whereby the 65 passing of each seam in the cloth will cause said marking-device to impart to said tape a corresponding marking for each seam.
20. In a cloth-measuring machine, the combination of a measuring-roll rotated in accordance with the travel thereover of cloth to be measured, suitable mechanism for presenting a supply of tape carrying equidistant markings constituting a scale, a floating cloth-roll superposed above said measuring-roll for pressing against it the cloth passing between said rolls and susceptible of being lifted by each seam of the cloth as it passes, a reciprocatory marking-device such as a needle positioned for marking upon said tape alongside of said scale, a pair of levers having their overlapped inner ends slotted to receive the shaft of said floating-roll so as to be moved by said roll on being lifted, and links pivoted at their outer ends to the outer ends of said levers and having their inner ends connected to said marking-device, whereby each seam in the cloth as it passes 100 will cause said marking-device to impart to said tape alongside of said scale a mark corresponding to said seam.

21. In a length-recording machine, the combination of a measuring-roll, a scale correlated to the revolutions of said roll, and means actuated by each seam in the cloth being measured as it passes over said roll, whereby such passage is recorded in proper relative position upon said scale.
22. In a machine for measuring the respective lengths of the successive different pieces of an article made up of a plurality of such pieces united by successive connections, the combination of a measuring-roll over which said article carries its said connections, a scale correlated to the revolutions of said roll, and means operated by the co-action of said roll with each successive connection for recording along said scale the respective lengths of said pieces. ¹⁵

FREDERICK B. VOEGELI.

Certificate of Correction.

Patent No. 1,630,039.

Granted May 24, 1927, to
FREDERICK B. VOEGELI.

It is hereby certified that error appears in the printed specification of the above-numbered patent requiring correction as follows: Page 6, line 37, claim 16, for the word "taped" read *tape*; and that the said Letters Patent should be read with this correction therein that the same may conform to the record of the case in the Patent Office.

Signed and sealed this 28th day of June, A. D. 1927.

[SEAL.]

M. J. MOORE,
Acting Commissioner of Patents.
